Inventor:
Alfred Smallwood,
By: B. Anger Atty.

UNITED STATES PATENT OFFICE.

ALFRED SMALLWOOD, OF LONDON, ENGLAND.

GRINDING OR DISINTEGRATING CEMENT OR OTHER MATERIALS.

1,262,115.

Specification of Letters Patent.

Patented Apr. 9, 1918.

Application filed April 18, 1916. Serial No. 91,941.

To all whom it may concern:

Be it known that I, ALFRED SMALLWOOD, a subject of the Kingdom of Great Britain, residing at 42 Hargrave Park, Highgate, 5 London, N., in the county of Middlesex, England, have invented certain new and useful Improvements in or Relating to the Means for Grinding or Disintegrating Cement or other Materials, of which the following is a specification.

This invention comprises certain improvements in or relating to the means for grinding or disintegrating cement or other material, and it refers more particularly to the 15 type of device, a number of which are used in connection with a tube mill, the said devices being in the nature of short cylindrical or like members which are placed within the tubular chamber in company with the material to be ground, in such a manner that the cylindrical or like members roll in relation to the wall of the chamber, and in relation to each other, thereby grinding or crushing the material. In the present invention I 25 employ cylindrical or like devices of a hollow character, and these are furnished with a recess or opening extending from end to end, but according to the present invention the external surface of the device is case-hardened, the inner or main structure of the device being allowed to remain of a springy or like character adapted to permit of temporary contraction. By this process a suitably hard grinding surface is obtained externally, while the inner part of the metal 30 is enabled to "give" in the event of an excessive stress, which might otherwise result in breakage.

In order that this invention may be clearly 40 understood and readily carried into practice, reference may be had to the appended explanatory sheet of drawings wherein Figure 1 is an end elevation of a grinding or crushing device, according to the present invention, and Fig. 2 is a side view thereof.

In a convenient embodiment of the present invention, the grinding devices *a* are each comprised of a tubular member, which latter is furnished throughout its entire 50 axial length with a longitudinal slit saw cut, or opening *b*, which latter is incorporated in such a manner as to leave a distinct space or gap which is enabled to partially or entirely close in the event of the 55 device being subjected to an excessive stress.

The device may be composed of metal of a springy or resilient character, whereby after being temporarily subjected to this stress, the device is enabled to recover its original form, the device being thus of a 60 resilient or springy character adapted normally to fulfil its function of grinding the material but furthermore adapted to "give" to a sufficient extent in the event of an excessive stress, which might otherwise result 65 in fracture.

For the purpose of providing a suitable grinding surface, the external surface of the grinding device is case-hardened, but I effect the case-hardening process in such 70 a manner that only the outer portion of the metal is case-hardened, the inner portion being allowed to remain of a character whereby the springy, tenacious, fibrous, or other qualities desired to permit of contraction 75 in the event of an excessive stress are preserved.

In order to carry out the case-hardening process in connection with only the external portion or layer of the metal, I fill the tube 80 internally with a suitable filling or insulating material, such as clay, prior to the case-hardening process, after which the devices thus prepared are subjected to the case-hardening process in the presence of appropriate case-hardening composition, with the result that the latter is unable to affect any part of the metal, except the external surface, in connection with which the process of case-hardening is desired. 85

After the case-hardening process has been effected, the filling may be removed, and a device is produced having a suitable grinding surface and possessing furthermore the quality enabling it to appropriately "give" 95 in the presence of an excessive stress, thus satisfactorily avoiding fracture.

What I claim as my invention, and desire to secure by Letters Patent is:—

A grinding element for a ball mill, consisting of a cylindrical shell having an opening in the wall thereof on one side only, and extending from end to end thereof. 100

In witness whereof I have hereunto set my hand in the presence of two witnesses. 105

ALFRED SMALLWOOD.

Witnesses:

ARTHUR BROWN,
HOLLIS BROWN.
